CLYDE H. TEESDALE, OF GRAND RAPIDS, MICHIGAN, ASSIGNOR TO TEESDALE MANUFACTURING COMPANY, OF GRAND RAPIDS, MICHIGAN, A CORPORATION OF MICHIGAN

FLOAT-OPERATED ELECTRIC SWITCH

Application filed November 22, 1930. Serial No. 497,391.

The present invention relates to controlling means for electric switches of the type shown in my Patent No. 1,760,382 and pending application Serial No. 209,419 filed July 30, 1927; and its object is, generally, to provide means of that character improved in certain respects hereinafter appearing; and more particularly, to provide such a switch controlled by a plurality of floats having combined and separate operations; and further, to provide such floats having a spacer member therebetween; and further, to provide such floats one of which carries during a portion of its movement a weight member; and further, to provide such floats one above the other and so arranged as to operate independently and in a sufficient depth of liquid; and further, to provide such floats arranged to exert their maximum effect in those portions of their movements wherein the switch is operated; and further, to provide means whereby the float may readily move within limits along a switch-controlling rod; and further, to provide a vacuum gage and means for closing the switch temporarily to operate the gage.

These and any other objects hereinafter appearing are attained by, and the invention finds preferable embodiment in, the organization hereinafter particularly described in the body of this specification and illustrated by the accompanying drawings, in which:

Figure 1 is an elevational view of a vessel adapted to contain liquid (as oil used in an oil-burning heater) having liquid-supplying means, an electric switch for governing the operation of said means and controlling means for the switch, a portion of the vessel being broken away;

Figure 2 is an elevational view thereof looking toward the right-hand side of Figure 1, certain parts being shown in vertical central section;

Figure 3 is a similar view of the same, but showing certain parts in another position;

Figure 4 is a similar view thereof, but showing said parts in still another position;

Figure 5 is an elevational view of the electric switch and controlling parts in the position assumed when the vessel's floats are in

the circuit-opening position seen in Figure 2;

Figure 6 is a similar view of some of the parts seen in Figure 5, but shown in the position assumed when the floats are in the circuit-closing position seen in Figure 3;

Figure 7 is a similar view of some of said parts, but shown in the position they assume when said floats are in the emergency circuit-opening position seen in Figure 4; and

Figure 8 is an elevational view of an installation of an embodiment of the invention in connection with an oil-burning heater, certain parts being shown in vertical section.

In the embodiment of the invention illustrated by these drawings, the oil-containing vessel 1 of an oil-burning heating installation is shown, supplied from a suitable source as the reservoir 2 (shown in Figure 8) by electrically-operated means, as a pump (indicated at 41) driven by an electric motor, said pump and motor being of usual construction and contained in a suitable casing 3 and housing 4 respectively. The electric circuit 5 containing said motor and a source of electric energy (not shown) has a circuit closer and opener or "switch" of any suitable type, preferably the mercury switch 6 as shown. This switch is carried, as by an embracing band 7, on a member 8 tiltable about a horizontal axis 9 to circuit-opening position seen in Figures 5 and 7 and to circuit-closing position shown in Figure 6. A spring 10, connected at 11 to the switch-carrying member 8 and at 12 to a lever 13 fulcrumed on a horizontal axis 14, extends in the closed position of the switch during the regular pumping operation of the motor below said axes as seen in Figure 6 and thus yieldingly maintains the lever 13, and the switch 6 with its carrying member 8 in the interrelative positions seen in that view wherein the circuit is closed. To the arm 22 of lever 13 is connected a depending rod 15 extending into the vessel 1. An upper float 19 (which may be called the "main" float) carried by the oil in the vessel has a vertical bore 20 through which said rod loosely extends. A lower float 18 (which may be called the "auxiliary" or "emergency" float) is secured as by the set screw 61 on the lower

end of this rod 15, and in the regular running operation of the organization supports as seen in Figure 2 a weight member 34 having a bore 35 through which said rod extends 5 loosely.

When oil, being exhausted from vessel 1 through its discharge pipe 30 leading to the oil-burning heater indicated at 31, reaches a predetermined low level, the bottom of the 10 main float engages the upper end 32 of the weight member which acts as a spacer block between the floats, and the descent of the upper float continuing, this float presses the lower float 18 downwardly until the upper 15 float and the weight member are supported in a resting position shown in Figure 3 on a stop or shelf 24 having a bore 36 through which the rod 15 loosely passes and an upright arm 25 held in vertically adjusted position 20 by means of a set screw 26.

In the regular operation of the organization, (sufficient oil being pumped into vessel 1) the floats rise, until the upper float 19 engages the collar 16 on rod 15 whereupon 25 the buoyancy of both floats being combined they exert their maximum lifting effect which is now sufficient to swing the arm 22 of lever 13 upwardly and cause the spring 10 to pass above the axes 9, 14 to suddenly raise arm 25 30 of member 8 and tilt the switch to circuit-opening position and stop the motor. The main or upper float 19 then rises from the upper end 32 of the weight member, the upward-movement of the lower float 18 having 35 been stopped by the shelf 24.

The parts are now in the positions shown in Figures 2 and 5. In the falling movement of the upper float it slides along the rod 15 until its bottom engages the upper end 32 of the weight member 34 whereupon the combined weight of both floats acts to move rod 15 downwardly far enough to cause the arm 22 of lever 13 to swing down and the spring 10 to pass below the axes 9 and 14, thereby 40 suddenly moving the switch to closed position and causing the pump to operate.

The parts are now in the positions seen in Figures 3 and 6. In the regular operation of the organization the parts thus move 45 between the positions shown in Figures 2 and 5 and the positions seen in Figures 3 and 6. The buoyancy of the two floats is thus desirably such that the action of both is required to throw the switch to the position 50 seen in Figure 5 and open the circuit in the regular operation of the organization, although prior to the engagement of the upper float with the collar 16 the lower float 18 has been exerting an upward pressure on rod 15; and until the upper float falls far enough to 55 engage the upper end of the weight member, the buoyancy of the lower float (as in the position of the parts shown in Figure 2) does not resist the upper float's falling movement.

60 Thus the pressure of the floats on the rod

15 and their action in moving the switch is exerted gradually to overcome the pressure of spring 10 and tilt the switch. The lower float 18 not only acts thus in the regular operation of the organization, but acts also as an emergency device. Should the oil become exhausted from the supply reservoir 2 or should it leak or be discharged in any manner from the vessel 1 faster than the pump supplies the same thereto or for other accidental causes should fail to be supplied to the vessel 1 in normal volume (although the motor be still in operation), the float 18 descends from the lowest position it assumes in the regular operation of the organization (seen in Figure 3) and moves the rod 15 still farther downwardly thus swinging the arm 22 of lever 13 to the position shown in Figure 7, which action moves the switch upwardly at its right hand end, thus opening 65 the circuit and causing the motor to cease running.

When the oil is supplied to the vessel 1 in sufficient amount the lower float 18 rises, and its buoyancy being sufficient for the purpose, it raises rod 15 far enough to move the switch to the closed position shown in Figure 6, whereupon the organization resumes its regular operation; and this action takes place although the buoyancy of the lower float is 70 not sufficient to raise the rod 15 high enough to throw the switch to the open position shown in Figure 5, this effect requiring that the upper float has risen high enough to engage collar 16, whereupon the lifting action of both floats combined opens the switch as 75 above described and as seen in Figure 5.

It will also be seen that by reason of the two floats and the arrangement of the parts as above described, a sufficient depth of oil 80 in the vessel is provided for the movement of the lower float between its positions shown in Figures 3 and 4 in its operation as an emergency device. The action of the lever 13 on the switch-carrying member 8 may be made 85 more positive than as accomplished by the spring 10, by the engagement of said lever's arm 37 with the arm 38 of said member, or said lever's arm 39 with said member's arm 40. The main float 19 is slightly weighted 90 at 42 on its bottom so that it may freely move along the vertical rod 15 without binding thereon.

A vacuum gage of common form in the pipe 21 is indicated at 43 in Figure 8; and inasmuch as the same cannot indicate the vacuum created by the pump unless the pump be running, means are combined with this gage and pump for closing the circuit 5 and causing the pump to operate for a sufficient time 95 to operate the gage when it is desired to read the same.

Such means for closing the identical switch 6 which controls the operation of the organization and for such a sufficient time is shown

in Figures 5 and 7, and comprises a horizontal bar 43 slidable in a bearing 44 against the pressure of a spring 46 and having an inclined end portion 45 with a shallow notch 47, this bar having also a lateral projection 50. When said bar is slid manually by its projecting handle 48 toward the left hand side of Figure 5, its inclined end 47 strikes the bent-over end 49 of rod 15 (or some projecting part of this rod or of arm 22) and raises arm 22 from its position shown in Figure 7 to that seen in Figure 6, the bent-over end 49 moving into said shallow notch; and the bar's projection 50 strikes a portion 51 of the switch-carrying member 8, to hold the switch closed until the hand is removed from the handle 48 permitting the spring 46 to slide the bar back.

But supposing the vessel 1 to be full of oil (or nearly so) and the parts in the position seen in Figure 5, the bar 43 on being pushed inwardly causes its projection 50 to engage the portion 51 of member 8 and closes the switch, but the bar's inclined end 45 does not strike the bent-over end 49 of rod 15, said bent-over end being in too high a position (when the vessel is full) to be thus engaged by the inclined end of the bar. Thus the position of this rod 15 is not interfered with although the switch is closed for a short time.

If in such full condition of the vessel 1 the switch be closed, oil pumped into the vessel will be returned through the overflow pipe 60 to the reservoir 2.

35 The invention being intended to be pointed out in the claims, is not to be limited to or by details of construction of the particular embodiment thereof illustrated by the drawings or hereinbefore described.

40 What is claimed is:

1. In an organization of the character described: a vessel adapted to contain liquid; an electric switch; upper and lower floats in the vessel having operative connection with the switch including a vertical rod having a stop, the rod being movable upwardly to open the switch and downwardly to close the same, the upper float having a downwardly limited movement and a movement between the stop and the lower float, the combined buoyancy of the floats and the combined weight thereof acting on the rod being requisite for opening and closing the switch respectively.

55 2. In an organization of the character described: a vessel adapted to contain liquid; an electric switch; upper and lower floats in the vessel having operative connection with the switch including a vertical rod having a stop, the rod being movable upwardly to open the switch and downwardly to close the same in the normal operation of the organization, and farther downwardly to open the switch in an emergency operation thereof, the upper

and a movement between the stop and the lower float, the combined buoyancy of the floats and the combined weight thereof acting on the rod being requisite for opening and closing the switch respectively in said normal operation, and the weight of the lower float in its farther downward movement and its buoyancy in its return upward movement being sufficient for opening and closing the switch respectively in said emergency operation.

3. In an organization of the character described: a vessel adapted to contain liquid; an electric switch; upper and lower floats in the vessel having operative connection with the switch including a vertical rod having a stop, the rod being movable upwardly to open the switch and downwardly to close the same; a weight member having a downwardly limited movement and a movement between the floats sustained by the lower float in an upper position thereof, the upper float having a downwardly limited movement and a movement between the stop and the weight member.

4. In an organization of the character described: a vessel adapted to contain liquid; an electric switch; upper and lower floats in the vessel having operative connection with the switch including a vertical rod having a stop, the rod being movable by the floats upwardly to open the switch and downwardly to close the same in the normal operation of the organization, and movable by the lower float to a lower position to open the switch in an emergency operation of the organization and reversely to close the same, the upper float having a downwardly limited movement and a movement between the stop and the hereinafter-mentioned weight member; a weight member having a downwardly limited movement and a movement between the floats sustained by the lower float in an upper position thereof.

5. In an organization of the character described: a vessel adapted to contain liquid; an electric tilttable switch; upper and lower floats in the vessel having operative connection with the switch including a swingable arm, a spring between the switch and the arm and a vertical rod connected to the arm and having a stop, the rod being movable by the floats upwardly to open the switch suddenly by the spring and downwardly to close the switch suddenly by the spring in the normal operation of the organization, and movable by the lower float to a lower position to open the switch in an emergency operation of the organization and reversely to close the same, the upper float having a downwardly limited movement and a movement between the stop and the hereinafter-mentioned weight member; a weight member having a downwardly limited movement and a movement between the floats sustained by

the lower float in an upper position thereof.

6. In an organization of the character described: a vessel adapted to contain liquid; an electric switch; a float in the vessel having operative connection with the switch including a vertical rod, the rod being movable upwardly to open the switch and downwardly to close the same; a weight member carried by the float in an upper position thereof and sustained independently of the float in a lower position thereof.

7. In an organization of the character described: a vessel adapted to contain liquid; an electric switch; upper and lower floats in the vessel having operative connection with the switch, and having vertical movements limited relatively to each other; a weight member carried by one of the floats in an upper position thereof and sustained independently of the same in a lower position thereof.

8. In an organization of the character described: a vessel adapted to contain liquid; an electric switch; a vertical rod connected with the switch for operating the same; a float in the vessel having a vertical bore through which the rod freely passes to a stopped position thereon, the float being weighted at its bottom for the purpose specified.

9. In an organization of the character described: a vessel adapted to contain liquid; an electric tiltable switch; a float in the vessel having operative connection with the switch including an arm swingable relatively to the switch, a spring between the switch and the arm for suddenly tilting the switch by the arm and a vertical rod actuated by the float; means for closing said switch comprising a bar manually slidable against the pressure of a spring and having an inclined end portion engaging the arm in one position thereof and a projection engaging the switch to tilt the same to closed position.

45 In testimony whereof I have hereunto set my hand at Grand Rapids, Michigan, this 8th day of November, 1930.

CLYDE H. TEESDALE.
